UNITED STATES PATENT OFFICE.

CHARLES T. GROSJEAN, OF GREEN POINT, ASSIGNOR TO TIFFANY & CO., OF NEW YORK, N. Y.

DESIGN FOR SPOON AND FORK HANDLES.

SPECIFICATION forming part of Design No. 11,968, dated September 21, 1880.

Application filed July 17, 1880. Term of patent 14 years.

To all whom it may concern:

Be it known that I, CHARLES T. GROSJEAN, a citizen of the United States, residing at Green Point, in the county of Kings and State 5 of New York, have invented and produced a new and original Design of Spoon or Fork Handle, of which the following is a specification, reference being had to the accompanying drawings, forming part thereof.

10 The features of novelty of this design of spoon or fork handle consist in an arrangement upon such a handle of the Indian chrysanthemum.

In the drawings, Figure 1 is a view of the 15 front, and Fig. 2 is a view of the reverse side or back, of a handle with said flower placed thereon.

On the front, from the ribbed shank *a* and undulating outline *b* the sharp-pointed leaves 20 *c* extend upward, wrapping over a cushion-like surface, partially covering or overlying interspersed chrysanthemum flowers *d*, the outer rib, *e*, of the shank widening as it ex-

tends upward, and terminating in a large flower, *f*, at the top of the handle, thus completing the design on the front. 25

The reverse side of the handle—namely, the back—is of a depressed form—that is, depressed toward the center *g*, extending the whole length of the handle, and rounding over 30 at the edge *h*. The ornamentation is similar to the front, but may be in lower relief; as shown in the drawings, and may extend down over quite a large portion of the bowl, as also shown in the drawings at *i*. 35

I claim—

1. The Indian chrysanthemum *d*, arranged on a spoon or fork handle, substantially as shown and described.
2. The ribbed shank and undulating outline, 40 with the chrysanthemum combined therewith, substantially as shown and described.

CHAS. T. GROSJEAN.
